2 Claims. (Cl. 166—7)

This invention is directed to a method for increasing ultimate recovery of oil from natural reservoirs. More particularly, the invention is directed to a method for increasing recovery of oil by cycling of hydrocarbons contained in the reservoirs.

Current oil production practices fail to recover much of the oil originally in place in natural reservoirs. As a consequence thereof, much effort has been devoted to devising methods of improving the ultimate recovery of the oil in the reservoirs. One such method for improving recovery of oil consists in displacing the reservoir oil with a hydrocarbon mixture as, for example, a hydrocarbon fluid usually containing methane and higher molecular weight hydrocarbon components. The solution of these components in the residual oil, especially the components less volatile than methane, leads to high oil recovery. An oil which has been diluted by extensive solution of these components (that is, lighter hydrocarbons such as ethane, propane, butane, pentane, etc.) or a natural gas which contains large quantities of these components is said to be "enriched."

This method, however, requires the injection of a large volume of the hydrocarbon mixture, which volume is difficult and expensive to obtain.

Most natural reservoir oils have dissolved in them large quantities of light hydrocarbons, such as methane, ethane, propane, butane, pentane, etc. When these lighter hydrocarbons are separated from heavier hydrocarbon components in a separator or distillation column, the resulting more volatile mixture is of a composition sufficiently enriched with intermediate hydrocarbons (ethane, propane, butane, etc.) as to give high oil recoveries. However, when oil is produced from a reservoir and separated into a light component phase and a heavy component phase and the light component phase compressed and reinjected into the formation, the reservoir pressure declines because of the removal of the heavy component phase. A pressure decline in the reservoir interferes with ultimate recovery of the oil.

Briefly, this invention comprises the steps of producing from a subsurface reservoir through a production well, separating the produced oil into a fluid phase containing light hydrocarbon components and a liquid phase containing heavier hydrocarbon components, injecting the light hydrocarbon components into the reservoir through a first injection well, the first injection well being spaced from the production well and then injecting the heavier hydrocarbon components into the reservoir through a second injection well, said second injection well being spaced from the production well and the first injection well.

An object of the invention, therefore, is to provide a method for improving recovery of reservoir oil by preventing or lessening reservoir pressure decline when displacing reservoir oil with a light hydrocarbon mixture separated from produced reservoir oil wherein the pressure decline inhibitor is easy and economical to obtain and consists of a recycled heavier hydrocarbon phase.

This and other objects of the invention will be apparent from a description of the invention taken in conjunction with the drawing wherein:

FIG. 1 is a schematic view illustrating one embodiment of the method of the invention; and

2

FIG. 2 is a schematic view illustrating another embodiment of the invention.

Referring to FIGS. 1 and 2 more specifically, numeral 10 designates the surface of the earth upon which are arranged injection wells 11 and 12, a production well 13, a separator 15, a pump and a compressor 17. An oil reservoir 14 is located below the surface of the earth 10 as shown. Injection wells 11 and 12 and production well 13 extend below the surface of the earth 10 to reservoir 14. On the surface of the earth production well 13 fluidly connects with separator 15, which is, in turn, connected to pump 16 and compressor 17.

As illustrated in the drawings a light hydrocarbon mixture is being injected through injection well 11, a heavy hydrocarbon liquid mixture is being injected through injection well 12 and oil is being produced through production well 13.

With this operation, in accordance with the embodiment shown in FIG. 1, an enriched fluid invaded zone 20 is created adjacent injection well 11; a non-enriched fluid invaded zone 21 is located adjacent zone 20; an original reservoir oil zone 22 is located between injection well 12 and zone 21; an oil and injected liquid zone 23 is located adjacent injection well 12 and an original reservoir oil zone 24 is located adjacent production well 13. Zones 22 and 24 may or may not exist depending upon the length of time the operation has been conducted.

The embodiment illustrated in FIG. 2 is similar except production well 13 is positioned between injection wells 11 and 12. Thus for the operation described supra an enriched fluid invaded zone 20 is formed adjacent injection well 11 and non-enriched fluid invaded zone 21 is adjacent zone 20. However, original reservoir oil zone 22 lies between production well 13 and zone 21 and injected liquid zone 23 extends from injection well 12 to zone 22.

In both embodiments reservoir oil is produced from production well 13 and sent to separator 15 where the oil is separated into a fluid containing the lighter hydrocarbon components and a liquid containing the heavier hydrocarbon components. The stripped fluid from the separator is sent to a compressor 17, as indicated by the arrowed line 25 wherein the fluid phase is compressed to a pressure sufficient to displace the reservoir oil. From compressor 17 the fluid is sent to injection well 11 as indicated by arrowed line 26. The stripped liquid from the separator is sent to pump 16, as indicated by arrowed line 27, wherein the liquid phase is pumped to a pressure sufficient to displace the reservoir oil. From pump 16 the liquid is sent to injection well 12, as indicated by arrowed line 28.

For the FIG. 1 embodiment the optimum location of injection well 12 is obtained in the following manner:

The practical size of the enriched fluid bank (zone 20) is limited by two factors. (1) After the injected liquid zone 23 reaches the production well 13, the produced fluid will yield much less light hydrocarbons than before. Continuing the operation involves recycling large quantities of oil which previously have been produced and stripped of lighter components. Therefore, to determine the optimum location of injection well 12, it is assumed that the return of stripped liquid to the reservoir will be stopped when stripped liquid begins to be produced from well 13. (2) When the enriching components of zone 20 reach injection well 12, the fluid injected through well 11 then will be dissolving in the liquid injected through well 12 and zone 20 will have ceased growing. Thus, the optimum location of liquid injection well 12 is such that zone 20 reaches injection well 12 at the same time that zone 23 reaches production well 13.

FIG. 2 is a schematic view illustrating another embodiment of the invention.

This location may be determined approximately as follows:

Laboratory displacement experiments are conducted wherein a model linear reservoir of length L' is completely charged with oil and connate water at actual reservoir temperature and pressure to simulate actual reservoir conditions. The model porous medium has permeability and porosity characteristics similar to the actual reservoir characteristics. A fluid hydrocarbon mixture of the same composition to be injected through injection well 11 is injected into one end of the model reservoir and oil is displaced and produced at the other end until the injected enriched fluid is first produced at the other end of the reservoir. The ratio E of the total volume of fluid injected per unit cross-sectional area of the experimental reservoir to the length of the experimental reservoir is evaluated at the time the injected enriched fluid is first produced.

For purposes of calculation a linear system is considered where L_1 is the distance between injection well 11 and injection well 12; l_1 is the length of zone 20 at any time; L_2 is the distance between injection well 12 and production well 13; l_2 is the length of zone 23 at any time; L is the total length of the reservoir; ϕ is the porosity of the reservoir; G is the cumulative volume (at reservoir conditions) of fluid injected into well 11 per unit of cross-sectional area of the reservoir; O is the volume of oil (at reservoir conditions) injected through injection well 12 per unit of cross-sectional area of the reservoir. Then, at any given time

$$l_1 = \frac{G}{E}$$

$$l_2 = \frac{G+O}{\phi}$$

As zone 20 reaches injection well 12 at the same time that zone 23 reaches production well 13,

$$l_1 = L_1$$

$$l_2 = L_2$$

and

$$L_1 + L_2 = L$$

Therefore,

$$(1) \quad \frac{L_1}{L} = \frac{l}{l + \frac{E}{F} + \frac{O}{\phi G}}$$

Similar relationships to determine the optimum location of injection well 12 can be derived for non-linear reservoirs. The value L_1 represents the minimum desirable value in all cases. In some instances, it may be desirable to relax the first restriction, that is to allow simultaneous production of injected oil and reservoir oil. Such recycling of the oil will permit L_1 to be made somewhat larger than indicated by Equation 1. However, this increase will be limited by the practical problems of handling the resulting large volumes of produced fluids.

In the embodiment of FIG. 2 the relative locations of production well 13 and injection well 12 are reversed. Thus, production is from the center of the reservoir and stripped liquid is injected into the end of the reservoir opposite the end wherein the fluid is injected. The optimum location of the production well in the center of the formation is determined by having the stripped injection liquid (zone 23) reach the production well 13 at the same time as the stripped injection fluid (zone 21) reaches production well 13. An additional factor F is employed which is similar to E , i.e., it is the ratio of the total volume of fluid injected per unit cross-sectional area of the experimental reservoir to the length of the experimental reservoir. However (F) is evaluated at the time of stripped gas (gas in equilibrium with the reservoir oil) breakthrough rather than at the time injected en-

riched fluid is first produced. Also the length of zone 21 is designated l_3 .

The location of the central production well 13 and the length of the enriched zone l_1 are determined as follows:

5

$$l_1 = \frac{G}{E}$$

10

$$l_1 + l_3 = \frac{G}{F}$$

$$l_2 = \frac{O}{\phi}$$

Since zones 21 and 23 reach the production well 13 at 15 the same time, then

$$l_1 + l_3 = L_1$$

$$l_2 = L_2$$

$$L_1 + L_2 = L$$

and

$$\frac{L_1}{L} = \frac{l}{l + \frac{FO}{\phi G}}$$

25

and the length of enriched zone 20 is

(2)

$$\frac{l_1}{L} = \frac{l}{\frac{E}{F} + \frac{OE}{\phi G}}$$

30 The ratio G/O in Equations 1 and 2 is equal to the gas-oil ratio (at reservoir conditions) of the fluid produced from well 13.

The choice of the arrangement for the injection wells and the production well is determined by which gives the 35 greater length of enriched zone L_1 .

At any desired time the recycling operation may be halted and extraneous gas injection initiated at injection well 11. This gas may be rich in intermediates or it may be a lean gas consisting principally of methane or 40 even of more insoluble materials such as air or nitrogen. Whatever type gas is injected, recovery of oil will be enhanced by the presence of the enriched zone 20.

For purposes of illustration the description herein refers to single fluid injection, liquid injection and production 45 wells. However, it is to be understood the invention encompasses the more practical arrangement wherein a plurality of fluid injection, liquid injection and production wells are used.

Having fully described the nature, objects, and operation of my invention, I claim:

1. A method for increasing recovery of oil from a subsurface reservoir comprising the steps of producing oil from said reservoir through at least one production well; separating said produced oil into only two phases, 55 a fluid phase containing substantially light hydrocarbon components having no more than 6 carbon atoms per molecule and a liquid phase containing substantially heavy hydrocarbon components having more than 6 carbon atoms per molecule; and simultaneously while producing oil from said reservoir, injecting said light hydrocarbon components into said reservoir through at least one first injection well to displace reservoir oil to said production well and said heavy hydrocarbon components into said reservoir through at least one second injection well to 60 inhibit reservoir pressure decline, said second injection well being located between said first injection well and said production well, and selectively spaced therefrom in a manner such that said light hydrocarbon components injected through said first injection well reach said second injection well at approximately the same time said heavy hydrocarbon components injected through said second injection well reach said production well.

2. A method for increasing recovery of oil from a subsurface reservoir comprising the steps of producing oil from said reservoir through at least one production well;

separating said produced oil into only two phases, a fluid phase containing substantially light hydrocarbon components having no more than 6 carbon atoms per molecule and a liquid phase containing substantially heavy hydrocarbon components having more than 6 carbon atoms per molecule; and simultaneously while producing oil from said reservoir, injecting said light hydrocarbon components into said reservoir through at least one first injection well to displace reservoir oil to said production well and said heavy hydrocarbon components into said reservoir through at least one second injection well to inhibit reservoir pressure decline, said production well being located between said first and second injection wells and selectively spaced therefrom in a manner such that said light hydrocarbon components injected through said

first injection well reach said production well at approximately the same time said heavy hydrocarbon components injected through said second injection well reach said production well.
